UNITED STATES PATENT OFFICE.

WILLIAM L. WATERS, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

CENTRIFUGAL WATER-GOVERNOR.

No. 836,580.

Specification of Letters Patent.

Patented May 5, 1908.

Application filed February 12, 1906. Serial No. 300,825.

To all whom it may concern:

Be it known that I, WILLIAM L. WATERS, a citizen of the United States, residing at Milwaukee, in the county of Milwaukee and 5 State of Wisconsin, have invented a certain new and useful Improvement in Centrifugal Water-Governors, of which the following is a full, clear, concise, and exact description, reference being had to the accompanying 10 drawings, forming a part of this specification.

My invention relates to governors and particularly to governors for controlling the circulation of water through the water jackets of compressors.

15 It is very desirable, where such compressors are not in service continually but are started and stopped, that the circulation through the water jacket thereof be also started and stopped at the same time to 20 economize in water. It has been the usual custom, where compressors were driven by electrical means, to control the water flow for the jacket by electromagnetic means usually controlled by the electric circuit for 25 the motor to actuate valving mechanism to start the water flow upon starting of the motor and to close the valving mechanism upon stopping of the motor. Such electromagnetic devices, however, involve a continuous 30 waste of electrical energy and are more or less unreliable owing to the fact that the windings thereof might burn out or otherwise become unserviceable.

My invention, however, contemplates a 35 direct mechanical connection between the compressor and the governor, and the governing mechanism is controlled by centrifugal force and is driven directly from the compressor either by belt or other connection.

40 The valving mechanism directly controlling the circulation has a normal tendency to allow such circulation, but is restrained from allowing such circulation when the compressor is idle or at rest. Upon starting of 45 the compressor, however, the valving mechanism is released to allow circulation of the cooling water through the compressor water jacket.

My invention will be best understood by 50 reference to the accompanying drawings, in which:

Figure 1 is an elevation view of the governor mechanism. Fig. 2 is a plan view thereof. Fig. 3 is a sectional view taken on line 3—3 of Fig. 2. Fig. 4 is a sectional view

taken on line 4—4 of Fig. 2, and Fig. 5 is a diagrammatic view of a compressor system showing the relation between the compressor and the governor.

The governor is comprised in a unitary 60 structure, of which the framework is composed of the base 1, the lower side walls 2 and 3 and the upper side walls 4 and 5, the side wall 2 supporting the lower half 6 of the bearing 7 and the upper wall 4 supporting 65 the upper half 8 of the bearing 7, while the lower wall 3 supports the lower half 9 of the bearing 10 and the side wall 5 supports the upper half 11 of the bearing 10, the two halves of the bearings 7 and 8 being secured 70 together by bolts 12 and 13, respectively. The base 1 is also provided with lugs 14 whereby the supporting frame may be secured to a support.

75 Journaled within the bearings 7 and 10 is a spindle or shaft 15 to the left end of which is secured the driving pulley 16, and the bearings also extend downwardly to form oil receptacles 17 and 18 for containing lubricating oil. The spindle 15 is provided with a 80 shoulder 19, and a collar or sleeve 20 supporting the flange or disk 21 is caused to rotate with the spindle by virtue of the key or screw 22, which screw, however, plays in an elongated keyway 23 whereby said sleeve 85 has also longitudinal movement on the spindle. A pin 24 driven through the spindle also limits the movement toward the left of said sleeve. Mounted between the shoulder 19 on the spindle and the shoulder 25 on 90 the sleeve 20 is the helical spring 26 whose tendency is to hold the sleeve and flange in a normal position to the left.

95 Extending from opposite sides of the spindle to the right of the shoulder 19 are the supporting wings 27—28 and 29—30, respectively, and pivoted at its elbow between the ends of the wings 27—28 is a bell crank lever 31, and pivoted at its elbow between the ends of the wings 29—30 is a similar bell 100 crank lever 32. A connecting link 33 pivots at 34 to the arm 35 of the bell crank lever 31 and at its other end is pivoted at 36 to the sleeve frame 20, as shown. A similar connecting link 37 pivots at 38 to the arm 39 of the bell crank lever 32, and at its other end is pivoted at 40 to the opposite side of the sleeve frame 20. The other arms 41 and 42 of the bell crank levers terminate respectively in balls 43 and 44. With this arrange- 110

ment upon rotation of the spindle 15, the balls will fly outwardly to rotate the bell crank levers and to move the sleeve and flange toward the balls against the force of the spring 26.

5 The lugs 45 and 46 on the supporting frame afford terminal supports for piping 47 and 48, respectively, and between said lugs and piping is secured the valve mechanism 10 49. The valve handle 50 is disposed in the path of the disk or flange 21 and, as best shown in Fig. 2, is held in a normal position thereby to close the passageway through the valve. A spring 51 secured to the valve 15 frame and engaging with the valve arm has a tendency to hold this arm in the dotted position shown, in which position the passageway through the valve is open. Upon rotation of the spindle and operation of the 20 governor balls the flange will be withdrawn and the arm 50 allowed to be moved toward its alternate position by the spring 51 and circulation may take place through the piping. The various operative parts of the 25 governor may be protected by a hood *h* engaging the edges of the side walls 2, 3, 4 and 5, and secured to the base in a suitable manner.

In Fig. 5 I have shown the electromotor *M* 30 utilized for driving the compressor *C*, although any engine, either electrical or mechanical, may be employed. The spindle 15 is shown connected with the motor by a belt 16, although this connection could be direct, as 35 by means of gearing. The compressor cylinder is surrounded by the water jacket *J* which is connected with a circulating system, here shown as comprising the tank *T* and the piping *P*, *P'*, the top of the tank connecting 40 with the top of the water jacket and the bottom of the tank connecting with the bottom of the water jacket, circulation being maintained in a well known manner by the difference in temperature of the water. Interposed in the piping *P'*, which carries the cool 45 water, is the valve 49, the parts 47 and 48 of the piping *P'* engaging with the valve, as shown in Figs. 1 and 2. When the motor and compressor are at rest the valve arm 50 will be held by the flange 21 in position to 50 close passageway through the valve. Upon starting of the motor, however, upon closure of the switch *S* connected with the supply circuit *a*, *b*, the spindle 15 will rotate and the 55 governor balls thrown outwardly to draw the flange 21 away from the arm which then is moved by the spring 51 to open the passageway through the valve, and cool water will then flow from the tank to and through the 60 water jacket, and upon becoming heated will flow to the top of the tank. Instead of utilizing a tank *T*, as shown, the valve may be connected directly with a hydrant or other source, and the heated water allowed 65 to flow from the water jacket.

As described, the tendency of the valve is always to continue the circulation so as to avoid any danger of the compressor ever running without water. The governing mechanism is substantially built, and the 70 first thing to give or break would be the spring 26, and if this spring should break the flange 21 would be unable to move the valve arm 50 to shut off the circulation and the only harm resulting would be continuous 75 flow of water after the engine stops, this, however, being much more desirable than to have the circulation closed upon the controlling mechanism becoming ineffective, in which case the compressor would be in 80 danger of destruction, owing to the failure of the cooling means therefor.

I do not wish to be limited to the exact construction and arrangement herein shown, as changes may readily be made without departing from the spirit of the invention.

What I claim as new and desire to secure by Letters Patent is:

1. In a governing device for governing the circulation of cooling water to the water jacket of a compressor, the combination with valve mechanism for inclusion in the circulating system, a detent frame normally engaging with the valve mechanism, centrifugal means normally holding said detent 90 mechanism to actuate the valve mechanism to prevent circulation, said centrifugal mechanism being adapted for connection with the driving means for the compressor, operation of the driving means and of the centrifugal 95 means causing movement of the detent frame whereby the valve mechanism will move to allow circulation.

2. In a governing device for controlling the circulation of water to the water jacket of a 105 compressor or other engine, the combination with a valve for inclusion in the circulating system, of a valve arm for said valve, spring means tending to hold said valve arm to open 110 passageway through the valve to allow circulation, centrifugal mechanism adapted for connection with a moving member of the compressor or other engine, said centrifugal means when the compressor or engine is at 115 rest being associated with the valve arm to prevent opening of the valve, and means upon movement of the centrifugal means by the compressor or other engine for causing the valve arm to be released to allow opening of said valve and consequent circulation.

3. In a governing device for controlling the circulation of cooling water through the water jacket of an engine, the combination with valve mechanism for connection with the circulating system, a detent frame, governor ball mechanism connected with said 125 detent frame and normally causing said frame to engage the valve mechanism to close passageway therethrough, means tending to move the valve mechanism to open 130

passageway therethrough, said governor ball mechanism being adapted to be driven upon movement of the driving means for the engine, said detent frame upon movement of the governor ball mechanism being moved to release the valve to allow said means to actuate the valve to allow passageway therethrough.

4. In a device for controlling the circulation of water to the water jacket of an engine, the combination with valve mechanism for connection with the circulating system, a shaft or spindle adapted to be driven upon movement of the driving means of the engine, ball governor mechanism mounted to travel with said shaft, a detent frame connected with said ball governor mechanism, and means tending to hold said valve mechanism in an open condition, said detent means being normally held in position by the ball governor mechanism to prevent opening of the valve, said governor mechanism upon movement of the driving means being operated to withdraw the detent means from the valve mechanism to allow said valve mechanism to be restored to its open condition.

5. In a governing device for controlling the circulation of cooling water to the water jacket of an engine, the combination with valve mechanism for connection with the circulating system, of means tending to hold said valve mechanism in an open condition to allow circulation therethrough, a shaft adapted for driving relation with the driving means for the engine, to be driven upon movement of said driving means, governor balls pivoted to travel upon rotation of said shaft, and framework connected with said balls adapted to reciprocate along said shaft upon rotation thereof, said framework being normally held in position to hold the valve mechanism in a closed condition to prevent circulation, said framework upon rotation of the shaft and operation of the governor balls being moved to release the valve mechanism whereby said valve mechanism may be returned to its open condition to allow circulation.

6. In a governing device for controlling the circulation of water to the water jacket of an engine, the combination with a valve for connection with the circulating system, of a valve arm or lever for said valve, means tending to hold said arm in position to open the valve, a shaft for connection with the driving means of the engine to be driven thereby upon movement thereof, pivot frames extending from said shaft, governor balls pivoted to said pivot frames, and a frame connected with said governor balls and adapted to reciprocate on said shaft, said frame being normally held in engagement with the valve arm to hold said arm in position to close the valve, said governor balls upon rotation of the shaft being thrown outwardly to withdraw the frame from the valve arm to allow the valve to be moved to its open position.

7. In a governing device for controlling the circulation of cooling water to the water jacket of an engine, the combination with a valve for connection with the circulating system, of a valve arm for said valve, spring means engaging said valve arm and tending to hold said valve in an open condition, a shaft adapted for connection with the driving means of the engine to be driven thereby upon movement thereof, a pivot frame secured to said shaft, governor balls pivoted to said pivot frame, a frame on said shaft connected with the governor balls and adapted to slide on said shaft as the balls are actuated, and a spring between said pivot frame and said slide frame tending to move said frame against the valve arm to cause closure of the valve, said governor balls upon rotation of the shaft being thrown outwardly to withdraw the slide frame to release the valve arm to allow the valve to be moved to its open condition.

8. In a governor device for controlling the circulation of cooling water to the water jacket of a compressor, the combination with a valve for connection with the circulating system, of means tending to hold said valve in an open condition to allow circulation, a shaft adapted for connection with a moving part of the compressor to be driven when the compressor operates and to be at rest when the compressor is at rest, a pivot frame secured to said shaft, governor balls pivoted to said pivot frame, a sleeve on said shaft connected with said governor balls and adapted to slide on said shaft as said balls are actuated upon rotation of the shaft, means for normally holding said sleeve in position to prevent rotation of said shaft for causing operation of the governor balls to withdraw the sleeve from engagement with the valve mechanism to allow opening of said valve.

9. In a governing device for governing the circulation of cooling water to the water jacket of a compressor, the combination with valve mechanism for inclusion in the circulating system, of an actuating frame normally engaging with the valve mechanism, centrifugal means normally holding said actuating frame to move the valve mechanism to prevent circulation, said centrifugal mechanism being adapted for connection with the driving means for the compressor, operation of the driving means and of the centrifugal means causing movement of the actuating frame whereby the valve mechanism will move to allow circulation.

10. In a governing device for controlling the circulation of water to the water jacket of a compressor or other engine, the combination with a valve for inclusion in the circulating system, of a valve arm for said

valve, mechanism tending to hold said valve arm to open passageway through the valve to allow circulation, centrifugal mechanism adapted for connection with a moving member of the compressor or other engine, said centrifugal means when the compressor or engine is at rest being associated with the valve arm to prevent opening of the valve, and mechanism upon movement of the 10 centrifugal means by the compressor or other engine for causing the valve arm to be released to allow opening of said valve and consequent circulation.

11. In a governor device for controlling 15 the circulation of cooling water to the water jacket of a compressor, the combination with a valve for connection with the circulating system, of spring means tending to hold said valve in an open condition to allow 20 circulation, a shaft adapted for connection with a moving part of the compressor to be driven when the compressor operates and to be at rest when the compressor is at rest, a pivot frame secured to said shaft, governing 25 balls pivoted to said pivot frame, a sleeve on said shaft connected with said governor balls and adapted to slide on said shaft as said balls are actuated upon rotation of the shaft, means for normally holding said sleeve in 30 position to prevent rotation of said shaft for causing operation of the governor balls to withdraw the sleeve from engagement with the valve mechanism to allow opening of said valve.

12. In a governor device for controlling 35 the circulation of cooling water to the water jacket of a compressor, the combination with a valve for connection with the circulating system, of means tending to hold said valve in an open condition to allow circulation, a 40 shaft adapted for connection with a moving element of the compressor to be driven when the compressor operates and to be at rest when the compressor is at rest, a pivot frame secured to said shaft, governor mechanism 45 pivoted to said pivot frame, a sleeve on said shaft connected with said governor mechanism and adapted to slide on said shaft as said mechanism is actuated upon rotation of the shaft, means for normally holding said 50 sleeve in position to prevent rotation of said shaft for causing operation of the governor mechanism to withdraw the sleeve from engagement with the valve mechanism to allow opening of said valve, said sleeve having a flange adapted for engagement with said valve to open or close said valve upon rotation of said shaft, and means upon said shaft whereby said sleeve is moved along said shaft a predetermined distance when 55 said valve is actuated.

In witness whereof, I hereunto subscribe my name this 7th day of February A. D. 1906.

WILLIAM L. WATERS.
